VENT DEVICE FOR HEATING SYSTEMS

George M. Ernst, Baldwin, N. Y.

Application July 2, 1937, Serial No. 151,581

2 Claims. (Cl. 137—122)

This invention relates to an improved vent device for heating systems.

It is known that when the heating fluid, such as steam, water vapor, or the like, is turned off, the residual fluid condenses, creating a partial vacuum in the heating system, and if the vent port of the radiator valve is then open air enters the radiator and the heating system until the pressure within the system is brought to atmospheric pressure. This tends to fill the heating system with air which must be expelled when by the generation of steam, pressure in the system is again raised. This retards the speed of circulation of the heating fluid, and delays the heating of the radiators.

One object of this invention is to provide an improved device for sealing a valve vented steam or vapor pressure heating system.

Another object is to provide a common seal for a valve vented steam or vapor pressure heating system.

Another object is to provide a vent valve which allows air to be expelled from the system when the pressure is raised, but is sealed to prevent the entrance of air into the system via the vent valve when said system is allowed to cool.

Another object is to provide an adapter for use in conjunction with the vent port of a conventional radiator valve, so as to allow air to be expelled from the valve, but to prevent the entrance of air into the system via the vent port of the valve when said system is allowed to cool.

Other objects will appear from the detailed description which follows.

35 In the drawing comprising but a single sheet of five figures numbered Figs. 1 to 5 inclusive.

Fig. 1 is an elevation of a radiator and radiator valve with my adapter attached;

Fig. 2 is a vertical sectional view of the adapter 40 mechanism;

Fig. 3 is an enlarged view of a detail;

Fig. 4 is a vertical sectional view of a modification showing a vent valve unit embodying my invention; and

45 Fig. 5 is a schematic drawing of a system embodying my invention.

Like reference characters designate corresponding parts throughout the several figures of the drawing.

50 Referring to Fig. 1 the radiator 25 is furnished with the customary valve mechanism 5, from which the valve cap has been removed and replaced by my adapter device 29, which is attached to the valve stem in any suitable manner, as by 55 means of a coupling 22 (Fig. 2).

Referring to Fig. 2, the adapter 29 consists of a metal casing 9 having a metal tube 20 passing through the wall of casing 9. Tube 20 terminates outside the casing in a coupling 22. Within the casing, tube 20 is threaded into a vertical ball 5 check valve body 14, which is in turn connected to an inverted U shaped metal tube 12, coupled by means of a suitable air tight coupling 11, to a tube 10 made of glass or other material adapted to resist the action of mercury. The lower end of 10 the metal casing 9 is suitably closed by means of a removable base cap 6. Within the casing 9, a reservoir 18 made or lined with any mercury resistant material such as glass, porcelain or the like, is placed; and to retain said reservoir in 15 fixed position relative to casing 9, a suitable packing material 8 may be inserted between the outer wall of reservoir 18 and the inner wall or casing 9. Reservoir 18 is partially filled with a quantity of mercury 7, and the lower end of the tube 10 20 is immersed in the mercury. A removable metal cap 13 encloses the upper end of casing 9. This cap is provided with a series of perforations or vent ports 16 to permit the free passage of air into and out of adapter 29.

25 The vertical ball check valve 14 which is best understood by reference to the sectional view shown in Fig. 3, includes a valve seat 19 having a ball check 17 normally seated on valve seat 19 under the influence of gravity. Metal tube 20 30 is screw-threaded into the threaded collar 23 of the casing of valve 14, and the inverted U shaped metal tube 12 is screw-threaded into the threaded collar 24 of the casing of valve 14.

The principle of operation is as follows:

35 When steam is generated in the heating system, the pressure in radiator 25 increases, lifting ball check 17 off valve seat 19 against the influence of gravity, and expelling air through the inverted U shaped metal tube 12, the tube 10, and the body of the mercury 7, through the interior of the adapter 29 and the vent ports 16 in the metal cap 13, to atmosphere. When all of the air has been expelled from the radiator 25 and the valve mechanism 5, the valve mechanism 40 closes in the usual and well-known manner to cut off the escape of steam.

45 When the heating system is allowed to cool, the reduced pressure in the system allows the ball check valve 17 to seat upon valve seat 19 and 50 seal metal tube 20, thus preventing the return passage of air into the valve mechanism 5 and the radiator 25. As the pressure in the system is reduced a partial vacuum is created below ball check 17 still further tending to retain the 55

ball check in seated position upon valve seat 19, while at the same time the partial vacuum thus created in the system causes a column of mercury to pass upwards in the tube 10 to seal the tube against entrance of air therein. The tube 10 may be of relatively small bore, a $\frac{1}{4}$ " tubing giving good results. Tube 10 should be long enough to prevent the column of mercury from reaching ball check valve 17, and from being lost in the heating system.

The valve mechanism 14 is not essential to the operation of the system, but merely serves as an auxiliary to the seal formed by the column of mercury in the tube 10. By the use of the vertical ball check valve 14 however, it is possible to reduce the length of glass tube 10.

The device 29 is an adapter for use with radiator vent valves now in common use. In new system installations it may be found desirable to 20 combine the valve mechanism 5 and my adapter 29 into a single vent valve unit structure, such as is disclosed generally in Fig. 4, wherein valve mechanism 15 replaces valve mechanism 5. The casing 9' is large enough to accommodate valve 25 mechanism 15, coupling 23, tubings 12 and 18, and receptacle 18 containing mercury 7. The nipple 21 of valve mechanism 15 may be attached to the radiator 25 in the usual way.

Instead of furnishing each radiator 25 with 30 an individual valve 5 and adapter 29 as shown in Fig. 1, or an individual vent valve unit structure as shown in Fig. 4, all of the radiator valves or valve mechanisms 5-5 may be connected to a common return pipe 30-30 (Fig. 5) having 35 its lower end located below the lowest radiator vent valve in the heating system. An adapter 29 of the general character shown in Fig. 2, but of somewhat larger capacity, may then be connected to the lower end of said common return pipe, thus furnishing one common mercury seal 40 for the entire heating system. This mechanism may omit the vertical ball check valve 14 entirely, wherever the system is adapted to permit the use of a tube 10 long enough to house a 45 column of mercury 27 inches or more in height.

Many variations of my system will occur to those skilled in the art.

What is claimed is:

1. An adapter for a heating system radiator 50 vent valve comprising, a receptacle for and resistant to the action of mercury, a quantity of mercury in said receptacle, a tube made of ma-

5 terial resistant to the action of mercury having its lower end submerged in the mercury contained in said receptacle, the mouth of said tube opening relatively close to the lower end of said receptacle to cause the mercury to seal the mouth of said tube when said receptacle is in upright position, said tube being adapted to vent gases through the mercury to atmosphere when the pressure in the tube is raised above atmosphere and to accommodate a column of mercury 10 mounting therein when the pressure in the tube falls below atmosphere, said tube being long enough to house a column of mercury of a height corresponding to the greatest sub-atmospheric pressure occurring in said tube under its normal 15 operating conditions, a portable tubular apertured metallic casing enclosing said receptacle and said tube and constituting a protective housing therefor, packing material positioned between the outer wall of the receptacle and the inner wall 20 of the casing, and means operable to secure said tube in said housing and to connect the upper end of said tube to the uncapped port of a radiator vent valve.

2. An adapter for a radiator vent valve comprising, a receptacle for containing a quantity of mercury to a given level, a tube having an end portion positioned within said receptacle with the mouth at the lower end of the said end system opening relatively close to the bottom of said 30 receptacle below the normal mercury level thereof to seal the mouth of the tube with mercury, said tube being operable to vent gases through the mercury to atmosphere when the pressure in the tube is raised above atmosphere and to accommodate a column of mercury when the pressure in the tube falls below atmosphere, said tube being long enough to house a column of mercury at a height corresponding to the greatest 35 sub-atmospheric pressure occurring in said 40 tube under normal conditions of operation, a portable apertured metallic casing forming a housing for said receptacle and for a portion of said tube, packing material positioned between the outer wall of the receptacle and the inner 45 wall of the casing, the upper end of said tube extending through the wall of said casing and projecting therebeyond, and a threaded coupling mounted upon the extreme upper end of said tube operable to secure said tube to the uncapped 50 port of a radiator vent valve.

GEORGE M. ERNST.
